UNITED STATES PATENT OFFICE.

HERMAN A. WEIDENBACH, OF BUFFALO, NEW YORK.

ROTARY PUMP.

1,280,601.

Specification of Letters Patent.

Patented Oct. 1, 1918.

Application filed August 22, 1917. Serial No. 187,511.

To all whom it may concern:

Be it known that I, HERMAN A. WEIDENBACH, a citizen of the United States of America, and a resident of the city of Buffalo, county of Erie, and State of New York, have invented certain new and useful Improvements in Rotary Pumps, of which the following is a full, clear, and exact description.

10 I have sought to provide a rotary pump which shall be efficient in its operation, and one which shall produce a plurality of pump impulses every revolution, thereby giving a substantially constant and uniform flow of 15 fluid.

Another object has been to provide a pump which shall be cheap to manufacture and simple in its construction and operation.

The above objects and advantages have 20 been accomplished by the device shown in the accompanying drawings.

In the drawings:

Figure 1 is a transverse, sectional elevation taken on line 1—1 of Fig. 2.

25 Fig. 2 is a longitudinal, sectional elevation taken on line 2—2 of Fig. 1.

Fig. 3 is a fragmentary, sectional view taken on line 3—3 of Fig. 1.

The pump comprises in general, an outer 30 casing 5; a rotor 6; and casing heads 7 and 8, secured one to each end of the casing.

The casing 5 is provided with a cylindrical bore 9 and with end flanges 10 and 10^a. Formed in the casing are a plurality 35 of inlet chambers 11, and a plurality of discharge chambers 12. The inlet chambers 11 extend from the left hand side of the casing, as viewed in Fig. 3, to the opposite side of the casing, where they open into the face 40 of the flange 10. The discharge chambers extend from the right hand side of the casing (see Fig. 1) to the opposite side thereof, where they open into the face of the flange 10^a. Connecting each of the inlet chambers 45 11 with the interior of the casing is an inlet port 13; connecting each of the discharge chambers with the interior of the casing is a discharge port 14.

The casing head 8, which is secured to 50 the flange 10 of the cylinder, is provided with an annular, inlet manifold 15. This manifold is connected with the inlet chambers 11 by means of manifold inlet ports 16, arranged one opposite each of the inlet 55 chambers. The casing head 7, which is secured to the flange 10^a, is provided with an

annular discharge manifold 17, and connecting this manifold with each of the discharge chambers 12 is a manifold discharge port 18. The inlet manifold 15 is provided with 60 a boss 19 to which is screwthreaded a suction or inlet pipe 20. The discharge manifold is likewise provided with a boss 21 to which is screwthreaded a discharge or outlet pipe 22.

Arranged between the inlet chambers 11 and discharge chambers 12 and their connected ports are radially sliding valves 23, 24, and 25, whereby these chambers and ports are separated. These valves are yieldably held in contact with the rotor by any suitable means, but preferably by the means shown. These means comprise a cylinder 70 26, screwthreaded into the casing in line with the top edge of each of the valves. Within the cylinder is slidably mounted a plunger 27, having a peripherally reduced lower end which contacts with the upper edge of the valve. A helical spring 28 is arranged within the cylinder and provides 80 the necessary pressure to the plunger. The valves 23, 24, and 25 slide within grooves cut into the casing 5, and a port 29 extends outwardly from each of the discharge chambers 12, thereby permitting the fluid under 85 pressure to come into contact with the upper edge of the valve, whereby it is not only balanced but the pressure serves to hold the valve in contact with the rotor.

The rotor 6 has a plurality of piston 90 chambers 30, 31, 32, and 33 formed in its periphery, the sliding valves being arranged to contact with the surfaces of these piston chambers. These chambers when passing the valves, act as additions to or continuations of the inlet and discharge chambers. The rotor is rigidly secured to a shaft 34, which is rotatably mounted in suitable bearings, carried by the heads 7 and 8.

When the pump is put in operation and 100 rotated in the direction of the arrow in Fig. 1 there will occur a number of successive pump impulses. A description of one of them will give a clear understanding of each of the others, and so, for convenience, I will 105 describe the impulse of but one piston chamber. Thus it will be seen that the fluid will be drawn from the inlet chamber 11, at the right hand side of the valve 23, through the port 13, and into the piston chamber at the 110 right of the valve 23. This chamber is, of course, increasing in volume as the rotor

continues to rotate, and, when its left hand edge has passed the valve 23, the fluid contained within this piston chamber will be transferred to the next succeeding discharge 5 chamber 12, and, as the piston chamber contacts with the valve 24, the fluid contained therein will be forced through the discharge port 14 and into the discharge chamber 12. It will be clear that while the fluid is being 10 discharged through the port 14, the part of the chamber on the other side of the valve is drawing in a charge of fluid from the inlet chamber 11, through the inlet port 13. Each time any one of the piston chambers passes 15 a valve, a charge of fluid is being discharged and drawn in.

In the drawings I have shown but three valves and a corresponding number of inlet and discharge ports. I have also shown four 20 piston chambers provided in the periphery of the rotor. By making the piston chambers of the rotor different in number from the number of valves, I get a number of successive pump impulses from each revolution 25 of the rotor, which give a substantially uniform and constant flow of fluid.

While I have shown and described the number of valves, inlet chambers, discharge chambers, and piston chambers above noted, 30 it will be obvious that I may provide any desired number of these parts and ports. These and other modifications may be made without departing from the spirit of my invention or the scope of the appended claims; 35 and I do not, therefore, wish to be limited to the exact embodiment herein shown and described.

Having thus described my invention, what I claim is:

- 40 1. A rotary pump comprising a casing and a rotor, the casing being provided with a plurality of inlet chambers, a plurality of discharge chambers, a plurality of inlet ports and a plurality of discharge ports, the rotor being provided with a plurality of piston chambers, in combination with radially reciprocating valves carried by the casing and engageable with the walls of the piston chambers of the rotor.
- 45 2. A rotary pump comprising a casing and a rotor, the casing being provided with a plurality of inlet chambers, a plurality of discharge chambers, a plurality of inlet ports and a plurality of discharge ports, the rotor being provided with a plurality of piston chambers greater in number than the inlet chambers, in combination with radially reciprocating valves carried by the casing

and engageable with the walls of the piston chambers of the rotor, whereby a series of successive pump impulses are produced for each revolution of the rotor.

3. A rotary pump comprising a casing and a rotor, the casing being provided with a plurality of inlet chambers, a plurality of discharge chambers, a plurality of inlet ports and a plurality of discharge ports, the rotor being provided with a plurality of piston chambers, in combination with radially reciprocating valves carried by the casing and engageable with the walls of the piston chambers of the rotor, and means for keeping the valves in contact with the periphery of the rotor.

4. A rotary pump comprising a casing and a rotor, the casing being provided with a plurality of inlet chambers, extending from one side of the casing to the opposite side thereof where they open into its under face, a plurality of discharge chambers, arranged reversely of the inlet chambers and extending from one side of the casing to the opposite side thereof, where they open into its under surface, a plurality of inlet ports, and a plurality of discharge ports, said rotor being provided with a plurality of piston chambers, in combination with radially reciprocating valves carried by the casing and engageable with the walls of the piston chambers of the rotor.

5. A rotary pump comprising a casing and a rotor, the casing being provided with a plurality of inlet chambers, extending from one side of the casing to the opposite side thereof where they open into its under face, a plurality of discharge chambers, arranged reversely of the inlet chambers and extending from one side of the casing to the opposite side thereof where they open into its under surface, a plurality of inlet ports, and a plurality of discharge ports, said rotor being provided with a plurality of piston chambers, in combination with casing heads arranged at each end of the casing, one casing head being provided with an inlet manifold and inlet manifold ports connecting the manifold with the inlet chambers, the other casing head being provided with a discharge manifold and discharge manifold ports connecting the manifold with the discharge chambers, and radially reciprocating valves carried by the casing and engageable with the walls of the piston chambers of the rotor.

In testimony whereof I have hereunto signed my name.

HERMAN A. WEIDENBACH.
